UNITED STATES PATENT OFFICE.

HENRY RUPPEL, OF CLEVELAND, OHIO, ASSIGNOR TO THE Dangler STOVE AND MANUFACTURING COMPANY, OF SAME PLACE.

SAFETY OIL-CAN ATTACHMENT FOR VAPOR-STOVES.

SPECIFICATION forming part of Letters Patent No. 404,439, dated June 4, 1889.

Application filed December 24, 1888. Serial No. 294,466. (No model.)

To all whom it may concern:

Be it known that I, HENRY RUPPEL, a resident of Cleveland, in the county of Cuyahoga and State of Ohio, a citizen of the United States, have invented a certain new and useful Improvement in Safety Oil-Can Attachments for Vapor-Stoves; and I do hereby declare the following to be a full, clear, and complete description thereof.

10 The nature of my invention relates to certain means for the purpose of shutting off oil or gasoline from the generator and needle-valve when the oil can or tank is lowered for filling, and raised to its former position to supply the burner when filled, whereby explosion and danger from the overflow of oil is prevented.

15 In the use of this improvement the oil is not cut off from the stand-pipe, but is arrested therein and prevented from passing therefrom to the generator heating-tubes or needle-valves when the oil-tank is returned from its lowered position to an upright one. A secondary movement or action is also required 20 to open the valve in the stand-pipe to allow the oil to flow therefrom to the generator. In supplying the stove with oil the tank is lowered, and by this movement a valve closes the passage from the stand-pipe to the generators, thereby extinguishing the burner, but not discharging the oil from the stand-pipe; hence on raising the oil-tank the oil will not 25 flow into the generators or through the needle-valve if open, thus preventing an overflow of the burner and protecting the person lighting the stove from the danger of the explosion or burning of the overflowed oil or gasoline. This overflow of oil will occur in 30 the ordinary drop-tank mechanism if the needle valve or valves are not securely closed. In lighting a stove of this kind there is a delay directly after the tank has been filled and raised, as the stand-pipe must be first filled from the tank before the generator can be 35 put in operation. In contradistinction to this, with my improvement the oil in the stand-pipe is not discharged therefrom, but is cut off by means of a valve from flowing into the generator and needle-valves when 40 the tank is lowered for filling. On raising the tank the said valve (which is between the

stand-pipe and generator) remains closed until opened by a secondary movement, as may be required in lighting the stove, whether it is or not to be lighted immediately, which then 55 will permit the passage of oil from the stand-pipe to the generator. The operation of the valve for the admission of oil to the generator is resultant of a secondary independent agency, which may be more or less delayed 60 after the tank is in its normal position.

Figure 1 is a sectional elevation of a vapor-stove, Plate 1. Fig. 2 is a vertical section of the stand-pipe, heater-plate, and attachments. Fig. 3 is a detached section in line *xx* of Fig. 65 2. Fig. 4 is a sectional view of certain mechanism employed in connection with parts involving the safety oil-feeding attachments, Plate 2.

Like letters of reference refer to like parts 70 in the several views.

In Fig. 1 A represents the heater-plate; B, the vapor-pipe; C, the needle-valve chamber; D, the oil tank or can; E, a part of the stove-frame, and G a corrugated burner-cap having slit-openings through the corrugations to the interior. In the stand-pipe F is a valve H, having its seat in the valve-rod guide H', Fig. 2. The upper part of the valve-stem J is supported in position and moves in the 75 guide H'. The stand-pipe is screwed into the short tube of the heater-plate, as seen at I, Fig. 2. To the lower end of the rod J is adjustably attached the lever K. The lower part of the rod is provided with a stuffing-box L, to prevent leakage of oil from the stand-pipe. The said rod is preferably threaded at M in the upper part of the stuffing-box, which is an extension from the lower end attachment of the T-shaped pipe N N', 80 screwed to the terminal of the stand-pipe F, as seen in the drawings, Figs. 2 and 3.

The valve-rod guide H' is fitted in the interior of the short tube O, projecting from the heater-plate A, between the annular shoulder S and the upper end of the stand-pipe, as 85 seen in Fig. 2. In the said guide I are one or more ports or openings P, through which the oil passes from the stand-pipe and valve H when open into the generator Q on the under side of the heater-plate A. The vapor 90 from the generator extends through the pipe 100

or conduit B to the needle-valve C, then through the air-tube R to the burner-cap G, Figs. 1 and 2. The tank-pipe D', which is in open relation or connection with the oil-conduit a, Figs. 2 and 4, extends down and turns in an angular direction to connect with the section N' of the T-shaped fitting or pipe N N' by being threaded into it, as seen at V, Fig. 4. The gland v of the stuffing-box V' is 5 screwed on the section N', Figs. 3 and 4, the pipe D' passing through the said stuffing-box, by means of which the connection of the jointed articulation of the pipe D with the section N' of the T-pipe is made oil-tight, at 10 the same time admitting the moving of the tank from D to D'', and vice versa, as herein-after more fully described.

Movably attached to the pipe D' is an arm W, arranged to operate the lever K at the terminal of the valve-rod J, Figs. 2 and 4. On moving the tank from D to D'', or a given intermediate point, the arm W on the pipe D' will so operate the lever K as to raise the valve-rod J by means of the screw M and 25 close the valve H, which will prevent the inflow of oil from the stand-pipe and oil-tank to the generator Q, thereby extinguishing the burner. The position D'' of the tank does not admit of the withdrawal of the oil from 30 the stand-pipe, as would be the case were the tank D lowered to the position D''', as is required in ordinary drop-tank mechanism. On raising the tank from D''' to D the oil will flow from the tank through the pipe D' up 35 into the stand-pipe E and overflow the stove if a needle-valve is forgotten or from any cause left open; hence, on lighting a stove in such condition an explosion or a dangerous fire will ensue, involving the person attending 40 it.

In the drop-tank arrangement as ordinarily used the tank is to be lowered to about the position D''', with the needle-valves closed, this position causing the oil to flow down out 45 of the stand-pipe F on a level with the oil in the tank at D'''. Now, the raising the tank from D''' to D causes the oil to pass up through the stand-pipe and out through the needle-valves if not perfectly closed, thus producing the overflow and the dangerous results 50 before mentioned, which results are avoided by the use of my improvement, as the tank is only moved from D to D'', in which position the stand-pipe F is full of oil and on a level 55 with the oil in the tank at D'', which movement of the tank D to D'' closes the valve H and cuts off the oil from the generator Q and needle-valve. The valve H remains closed after the tank is raised, which prevents the 60 lighting of the stove until the operator so moves the lever K by the handle K' as to open the valve H, allowing the oil to flow from the stand-pipe into the generator Q, Figs. 2 and 4.

On lowering the tank D the valve H is 65 closed to shut off the inflow of oil from the stand-pipe to the generator after the tank is moved back to its normal position. Then by

a reverse motion of the valve-stem J, by means of the handle K', the valve H is opened for the inflow of oil to the generator from the stand-pipe in the manner described. However, this opening of the valve H may be more or less delayed after the tank is raised. This secondary movement of the valve-rod for opening the valve is arrested by the contact 70 of the lever K with the arm W until the tank D is up in position, as shown in Fig. 1.

As shown in Figs. 2 and 3, it is supposed that the valve H has been opened by the secondary movement of the handle K', which 80 again sets the lever K in contact with the arm W, whereas the dotted lines d in Fig. 3 indicate the position of the lever K, into which it is turned when the tank is lowered for filling.

By means of the mechanism described the inflow of oil to the generator and needle-valve is effectually shut off and the burners extinguished on lowering the tank for refilling, or for other purposes, remaining cut off until 90 supplied, as described, by swinging the tank to its original position.

To relight the stove, the valve H must be first opened before any oil can be admitted to the generator, whether the needle-valve is 95 opened or not, as the valve H controls the supply of liquid fuel to the burner as may be required, with or without the use of the vapor or plug valve at c.

The improvement herein described is shown 100 in connection with one burner. The same arrangement of mechanism is, however, applicable to two or more burners without departing from the essential features of my invention. The pipe b, Figs. 3 and 4, represent 105 an attachment by which the said mechanism may be extended to other burners of the same stove. The lever K and arm W are respectively so adjustable on the valve-rod J and tank-pipe D' as to be moved, set, and secured by the set-screws in the required position for opening and closing the valve H on moving the tank D, as and for the purpose described.

What I claim as my invention, and desire to 115 secure by Letters Patent, is—

1. In combination with a vapor-stove, a stationary stand-pipe F, carrying the burner, a valve in said stand-pipe, a reservoir and a pivoted supply-pipe D', leading therefrom to 120 the stand-pipe, an arm on the supply-pipe, and an extension, as K, connected to the valve in the stand-pipe and located directly in the path of the arm on the pipe D', substantially as described.

2. In combination with a vapor-stove, a stationary stand-pipe F, carrying the burner, a valve in said stand-pipe, a reservoir and a supply-pipe D', leading therefrom to the stand-pipe, pivotally connected therewith, an adjustable arm W on said pipe D', and an extension K, adjustably connected to the valve in the stand-pipe and located in the path of the arm W, substantially as described.

3. In combination with the burner of a vapor-stove, generating-conduits leading thereto from the stand-pipe, a valve for controlling the burner, a second valve between the stand-pipe and the valve of the burner, a reservoir, a pivoted supply-pipe D', supporting the same, and intermediate operating devices between the pivoted supply-pipe D' and the stand-pipe valve, substantially as described. 15
- 5 4. In combination with a vapor-stove, a stationary stand-pipe F, a valve within the same for controlling the passage leading to the generating-conduits, an extension K connected to said valve, a reservoir and a pivoted supply-pipe for the same, an arm W on said supply-pipe, adapted to come in contact with the extension K of the valve to automatically operate the same, and a handle connected to said valve for operating the same manually, substantially as described. 20
- 10 In testimony whereof I affix my signature in presence of two witnesses.

HENRY RUPPEL.
